UNITED STATES PATENT OFFICE

95,902

DESIGN FOR A FIRE EXTINGUISHER

Powell Evans, Haverford, Pa.

Application April 12, 1935, Serial No. 56,351

Term of patent 14 years

To all whom it may concern:

Be it known that I, Powell Evans, a citizen of the United States, residing in Haverford, Montgomery County, Pennsylvania, have invented a new, original, and ornamental Design for a Fire Extinguisher, of which the following is a specification, reference being had to the accompanying drawing, forming a part thereof, in which

Fig. 1 is a side elevation of a fire extinguisher showing my new design; and
Fig. 2 is a front elevation thereof.

I claim:
The ornamental design for a fire extinguisher, substantially as shown.

POWELL EVANS.
